[57] CLAIM

The ornamental design for a faucet body, as shown and described.

DESCRIPTION

FIG. 1 is a front view of our new design of a faucet body, a rear view of our new design of the faucet body being a mirror image of the front view thereof; FIG. 2 is a top view of our new design of the faucet body;

FIG. 3 is a bottom view of our new design of the faucet body;

FIG. 4 is a left side view of our new design of the faucet body, a right side view of our new design of the faucet body being a mirror image of the left side view thereof; and,

FIG. 5 is a perspective view of our new design of the faucet body.

The broken line representation of knobs, spout and hub from which the spout extends in FIG. 5 are for the purposes of illustration only and form no part of the claimed design.
